United States Patent Office.

EDWARD S. POUCHER, OF NEW YORK, N. Y.

Letters Patent No. 90,390, dated May 25, 1869.

IMPROVED CARPET-CLEANING MACHINE.

The Schedule referred to in these Letters Patent and making part of the same.

To all whom it may concern:

Be it known that I, EDWARD S. POUCHER, of New York, in the county of New York, and State of New York, have invented certain new and useful Improvements on Carpet-Cleaning Machinery; and I do hereby declare that the following is a full, clear, and exact description thereof, reference being had to the accompanying drawings, making part of this specification, in which—

Figure 1 is a section, taken through the machine in the vertical plane indicated by line α in fig. 2, representing the machine as it would appear when erected and in operation.

Figure 2 is a front elevation of the machine.

Figure 3 is a side view of the machine when folded.

Figure 4 is a sectional view in detail, showing one of the revolving tappets arranged to act upon the pivoted end of a beater.

Figure 5 is a sectional view of a suction-device for carrying off the dust.

Similar letters of reference indicate corresponding parts in the several figures.

This invention relates to certain novel improvements on machinery for cleaning carpets by beating and brushing them.

The nature of my invention consists—

First, in a novel combination and arrangement of beating-arms, with endless belt-guides, brushes, and rollers, and also with a portable folding-frame, whereby the operations of beating and sweeping can be performed with great facility and perfection, and whereby the machine can be made to occupy a very compact space when not in immediate use, as will be herein-after explained.

Secondly, in the arrangement upon a suitable frame of a series of alternately moving beating-arms, so that these arms shall lie at right angles to the direction of movement of the carpet, and strike from opposite sides of the carpet, while passing between them and a series of endless-belt supports, as will be hereinafter explained.

Thirdly, in the application of cloth guides to the carpet-rollers, with clasps or hooks applied to the edges of said guides, as will be hereinafter explained, whereby the entire length of carpet can be guided and kept smooth while passing beneath the beaters.

Fourthly, in combination with the carpet-cleaning machine, a suction-fan for carrying off the dust, as will be hereinafter explained.

To enable others skilled in the art to understand my invention, I will describe its construction and operation.

The frame, which is adapted for containing the carpet-cleaning devices, is composed of two sections, A and B, united together by hinges α , and provided with

a pivoted hooked tie, B', so that this frame can be erected for operation, as shown in figs. 1 and 2, or folded, as shown in fig. 3, when not in use.

By having hooks b applied to the lower ends of the frame A, this frame can be secured firmly down upon a foundation or floor, A², by using staples or other fastenings, in combination with the said hooks.

The frame A consists of two parallel beams, secured together by cross-beams A¹ A', in a rigid manner, the ends of which extend out beyond the said beams, and adapted to form bearings for two tappet-carrying shafts E E'.

At or near the extreme ends of this frame, and arranged parallel to the beams A¹ A', are rollers D D², one of which, D, receives the carpet around it, and pays it off or rolls it up, and the other, D², which is flanged, serves to guide the carpet while passing to or from a carpet-roller, D. This latter roller D² has its bearings in the frame B, and serves the same purpose as the roller D at the base of the frame-section A.

To each one of the two carpet-rollers D D², I permanently affix a piece of canvas, S, indicated in blue in fig. 1, which has hooks or caps, h h, attached to its free end, and which should be nearly or quite as long as the distance between the two rollers D D².

The object of these canvas strips S is to guide the carpet beneath the beaters smoothly, and also allow the ends of the carpet, which are fastened to the ends of these strips, to be properly beaten and kept stretched while being beaten.

Between the two rollers D D², and having their bearings in the longitudinal beams of frame A, are two belt-rollers C C', over which a number of narrow belts, e e e, pass, arranged at suitable distances apart, so as to afford a support for the carpet while being beaten.

The lower roller, C, receives rotary motion from a hand-crank, K, or from a convenient prime-mover, acting through the medium of a belt passing around a fast drum, L. On one end of the shaft of roller C, a belt-drum, k, is fastened, which communicates rotary motion to the carpet-roller D, through belt j and drum k'; and on both ends of the shaft of roller C' bevel spur-wheels d d are keyed, which engage with pinion spurs d' d' on tappet-shafts E E', and communicate rotary motion thereto.

The uppermost roller, C, receives rotary motion from the lower roller C', through the medium of the belts or bands e e e, and communicates rotary motion to carpet-rollers D², through belt c, and also to the brush-roller F, through a belt passing around pulleys m m', as shown in figs. 2 and 3.

The brush-roller F is arranged between the rollers C D², for sweeping or brushing the carpet while passing to or from the beaters.

The beaters *s s s* are equally divided upon opposite sides of the frame *A*, and are all arranged parallel to the rollers over which the carpet is drawn, and about which it is wound, as shown in fig. 2.

These beaters are pivoted to short standards *t*, fastened to and rising from the side beams of frame *A*, so that they will vibrate freely.

The shortest arms of these beaters, which are suitably shod with metal, and bevelled, as shown in fig. 4, are acted upon by tappet-rollers *i i*, which are secured in pairs to short arms on shafts *E E*; and the beaters are caused to strike the carpet by the action of springs *n n* upon them. The tappet-rollers *i* raise the beaters free from the carpet, and the springs *n n* cause the beaters to strike suddenly upon the carpet when the beaters are released from said rollers.

The tappets are arranged upon their respective shafts so as to cause the beaters to alternate with each other in their blows.

I employ, in conjunction with my improved carpet-cleaner, a suction-device for carrying off most of the dust which is driven out of carpets.

This device consists of a horizontally-arranged case, *G¹*, mounted upon legs *G²*, and constructed with a large upwardly-flaring receiving mouth, *G*.

Within the case *G*, and suitably supported in bearings, is a shaft, *g*, carrying on one end a belt-pulley, *g'*, and having applied to it, within the said case, a spiral flange, *G²*, by the rapid rotation of which a strong descending draught is created in the direction of the arrows in fig. 5.

In practice, this suction-device is arranged beneath the frame *A*, and its flange *G²* is rotated by means of a belt, *p*, which is passed around pulleys *P g'*. As the dust is driven out of a carpet by the beaters and brush, as above described, it will be drawn into the spout *G*, and discharged from case *G¹* into a trunk, leading off to any convenient place.

To operate the machine, a carpet is fastened by one

end to one end of the canvas *S* on roller *D*, and rolled thereon. The free end of the canvas *S*, attached to the roller *D'*, is then drawn down between bands or belts *e* and the beaters *s*, and its end attached to the free end of the carpet. Thus the carpet will be fastened at both ends to the two canvas strips, and by unrolling it from *D* and rolling it upon *D'*, at the same time actuating the beaters and brush, the carpet will be cleaned.

After the last end of the carpet leaves the roller *D*, it will be held by the canvas strip and allowed to pass beneath the entire number of beaters, and also beneath the brush. By then reversing the motion of the machine, the carpet can be returned beneath the beaters, and moved upon the roller *D* again.

Having described my invention,

What I claim as new, and desire to secure by Letters Patent, is—

1. The combination of a portable folding frame *A* *B*, having beating arms *s*, a brush, *F*, and carpet-rollers *D D' D'*, arranged upon it, substantially as and for the purposes described.

2. The combination of the suction-device *G G¹ G²* with the carpet-cleaning machine, substantially as described.

3. Tappet-carrying shafts *E E*, arranged so as to be driven by roller *C'*, and to operate upon beaters, which are pivoted on opposite sides of frame *A*, substantially as described.

4. The combination of the endless bands *e e* with the beaters *s s s*, and carpet-rollers, substantially as and for the purposes described.

5. In combination with the folding frame *A B*, the rollers *D D' D'*, and the beating-arms *s s s*, arranged substantially as described.

EDWD. S. POUCHER.
